FRANK W. DOWNE, OF SAN FRANCISCO, CALIFORNIA, ASSIGNOR TO MECHANICAL
PERFECTING CORPORATION.

MACHINE FOR RECORDING AND REPRODUCING SOUND.

Application filed June 20, 1916. Serial No. 104,656.

To all whom it may concern:

Be it known that I, FRANK W. DOWNE, a subject of the Kingdom of Great Britain, residing at the city and county of San Francisco, State of California, have invented certain new and useful Improvements in a Machine for Recording and Reproducing Sound, of which the following is a specification.

10 My invention relates to a machine for recording and reproducing sound, and in the embodiment shown, is adapted for recording speech on a rotating cylinder and for reproducing speech on the same instrument. As machines for recording and reproducing sounds are now well known in the art and consist of certain essential parts which may be briefly described as follows, to wit:—a recording cylinder upon which 15 a sound record may be made; means for rotating the recording cylinder; a sound box; a recording stylus; a reproducing stylus; means for moving the sound box along the sound record; and means for moving the 20 respective styli into and out of operative position to record or reproduce, as desired—

I will not enter into any extended description of the parts enumerated, but merely refer to them for the purpose of 25 identification, and confine the description to those features which I believe to be new and original with me.

The features of novelty which I consider new and desire to secure by Letters 30 Patent, are:

First: The construction of the case which contains or supports the operative parts.

Second: The construction and location of the mechanism on the front of the case 40 which controls the operation of the motor device.

Third: The construction of the mechanism for supporting the record cylinder.

Fourth: The construction of the mechanism 45 for taking up the wear of the bearings of the mechanism which supports and rotates the record cylinder.

Fifth: The construction of the sound box and the mechanism acting in conjunction therewith, by reason of which the recording or reproducing stylus is thrown, as desired, into operative position relative to the record cylinder.

Sixth: The construction of the mechanism 50 whereby the sound box and its sup-

port may be quickly moved at will longitudinally of the record cylinder.

Seventh: The construction of the mechanism whereby the sound box and its support may be given a step-by-step movement 60 in either direction along the record cylinder.

Eighth: The construction of the mechanism whereby printed indications are impressed upon a slip of paper carrying a 65 scale, indicative to the person reproducing from the cylinder, the characteristics of the record on the cylinder, or acts to be performed by the person effecting the reproduction. 70

Ninth: The construction of the mechanism, whereby removal of the cylinder from the machine cannot be effected until the styli carried by the sound box, are moved out of relation with the record cylinder. 75

The above are the main features of novelty embodied in my improved machine. Other features of novelty exist, which will be referred to in the specification, separately or in connection with such enumerated features. 80

The accompanying drawings will serve to illustrate my invention, in which, Fig. 1 is a front elevation, the parts being shown in section in order to illustrate the means employed for mounting and driving the record cylinder. Fig. 2 is a transverse section taken on the line II—II of Fig. 1. Fig. 3 is a face view of the upper side of the top portion of the machine. Fig. 4 is 85 a longitudinal section on the line IV—IV of Fig. 3. Fig. 5 is a detailed view showing the spacing mechanism, with the spacing pawls in a different position from that shown in Fig. 4. Fig. 6 is an end view and 90 illustrates in full and dotted lines the respective positions of the devices used to prevent removal of the record cylinder during certain positions of the sound box. Fig. 7 is a transverse section, taken approximately on the line VII—VII of Fig. 4. Fig. 8 is a longitudinal section taken approximately on the line VIII—VIII of 95 Fig. 7. Fig. 9 is a sectional elevation of the device employed in connection with the machine for determining the current fed to the electric motor which actuates the record cylinder of the machine. Fig. 10 is a horizontal section taken on the line X—X of Fig. 9. Fig. 11 is a detailed view of the 100

Fig. 11 is a detailed view of the 105

outside of Fig. 9 and illustrating the scale and adjusting nut as employed for regulating the current.

Referring to Figs. 1 and 2 of the drawings; A is the supporting frame of the machine. The frame is divided into two parts, the part B which consists of an oblong box in which is located the driving mechanism, and the part C, hinged to the part B at D, which serves as a cover for the box B and a support for the sound recording and reproducing mechanism.

Situated on the front of part C, is a plate E, and arranged on this plate is a switch F for controlling the motor and also a speed regulating device G, and an air controlling device H for the motor. The plate E may be omitted, and the devices F, G, H, may be directly mounted upon the portion C of the frame. The front portion of the frame C is inclined, as shown in Fig. 2. The upper surface of the frame C has formed in it a concaved receptacle I, which is inclined in a downward direction from left to right of Fig. 1, from the point J to the point K. The purpose of this receptacle I is to receive particles of the record cylinder as they are cut off by the recording stylus. The particles which accumulate in this receptacle may be swept out by means of a brush moved from the end J to the end K. I do not consider this cavity I as an essential element, as the top of the case may be formed flat, as indicated in dotted lines in Fig. 2, and a pan as usually employed, used to receive the particles.

Projecting upward from the opposite ends of the frame, are two vertical standards L—M. These standards are provided with forwardly projecting arms N—O (see Fig. 3) which serve as a support for a recessed plate P, adapted to carry a series of strips of paper Q on each of which is printed a scale R. Arranged in front of the plate P, to which it is secured, is a second scale S. The purpose of the strips of paper and the scales will be hereafter explained.

The standard M has formed in it, a slot T, and in this slot is located a curved arm U, which is mounted on the end of a twisted strip V, which has its bearings in the standards L—M. The purpose of the twisted strip and the arm U, and its relation to the other parts of the device, will be hereinafter described.

Projecting upward from the left hand side of the frame C is a standard W, in which is formed a bearing X for a spindle Y upon which the record cylinder is mounted. Supported by and having its bearings in the standards L—M is a threaded shaft Z, upon which the sound box carriage is mounted. As the mechanism which is used to drive the shaft Z and to move the sound box longitudinally along the record cylinder,

presents no features of novelty, I will merely refer to it generally. Such mechanism is located in the lower portion B of the case, and consists of a motor 5, speed regulator 6, controlled by the speed regulating device G 70 on the outside of the case, an electric switch 7, controlled by the switch F on the outside of the case, an air control device 8, controlled by the air control H on the outside of the case. The air control device 8, controlled by the air control H as more clearly shown in Figure 1, operates as a pneumatically operated clutch for engaging and disengaging the belt 9 and pulley carrying the same from the motor shaft. The movement of the motor is transmitted through a belt 9 to a pulley 10 mounted on the spindle Y. Motion is communicated from the spindle Y to shaft Z, by means of the gear 11 mounted on spindle Y and interposed 85 gears 12—13—14, which have their bearings in the standard L, and gear 15 mounted on shaft Z (see Fig. 2). The pulley 10 is provided with a hub 16, in which are a series of spaced recesses 17. In each of these recesses is a spring 18, and in front of the springs, hard steel pins 19. These pins bear against the outer surface of the gear 11, which latter has suitable connection with the spindle Y, as by the spline connection 90 11a. The object of this arrangement is to take up any wear between the inside of the standard W and a collar 20 on the spindle Y, thus insuring alinement of the spindle and preventing longitudinal vibration 100 of the spindle during operation of the machine.

I will now describe the support for the record cylinder. Mounted rigidly on the spindle Y to the right of the standard W, 105 is a plate 21 which may be made integral with the collar 20. This plate has formed in its circumference three equally spaced radial slots or openings 22, and pivoted to the plate 21 in each of these openings is a bell-crank 110 23. Mounted loosely on the spindle Y, and in front of the plate 21, is a disc 24, in which are formed three openings 25, registering with the openings 22. The disc 24 is normally pressed against the plate 21 by a 115 coiled spring 26 surrounding the spindle Y, which bears at one end upon the disc 24, and at the other end upon a ring 27, surrounding the spindle Y. The ring 27 is held in position by means of a pin 28 situated in 120 front of the ring 27, and projecting from the spindle Y.

Mounted upon and enclosing the right hand end of the spindle Y, is a tube or sleeve 29, formed with a transverse flange 30, in 125 which are three equally spaced openings 31. The tube 29 is slidably and non-rotatably mounted on the spindle Y, in position with the openings 31 registering with the openings 25 in the disc 24, by suitable means. 130

- As here shown the tube has formed in it a slot 32, and located in this slot and connected to the spindle Y, is a screw 33. The outer end of the tube 29 is provided with a 5 ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ ²³⁵ ²⁴⁰ ²⁴⁵ ²⁵⁰ ²⁵⁵ ²⁶⁰ ⁵⁶¹⁰ ⁵⁶¹⁵ ⁵⁶²⁰ ⁵⁶²⁵ ⁵⁶³⁰ ⁵⁶³⁵ ⁵⁶⁴⁰ ⁵⁶⁴⁵ ⁵⁶⁵⁰ ⁵⁶⁵⁵ ⁵⁶⁶⁰ ⁵⁶⁶⁵ ⁵⁶⁷⁰ ⁵⁶⁷⁵ ⁵⁶⁸⁰ ⁵⁶⁸⁵ ⁵⁶⁹⁰ ⁵⁶⁹⁵ ⁵⁷⁰⁰ ⁵⁷⁰⁵ ⁵⁷¹⁰ ⁵⁷¹⁵ ⁵⁷²⁰ ⁵⁷²⁵ ⁵⁷³⁰ ⁵⁷³⁵ ⁵⁷⁴⁰ ⁵⁷⁴⁵ ⁵⁷⁵⁰ ⁵⁷⁵⁵ ⁵⁷⁶⁰ ⁵⁷⁶⁵ ⁵⁷⁷⁰ ⁵⁷⁷⁵ ⁵⁷⁸⁰ ^{5785</}

both styli into a neutral position, or otherwise into a position where the record cylinder can be placed on or taken off of the spindle without being brought into contact 5 with the styli (such contact being likely to injure them) and the record cylinder moved transversely of the machine.

The arm 42 of the carriage 40 is bifurcated at its lower end to form the arms 59, 10 which are disposed on opposite sides of a rod 60 secured in the standards L—M. The upper surface of this rod is provided with a rack 61 (see Figs. 4 and 5). It will be understood that the purpose of the arms 15 59 and rod 60, leaving out of consideration the rack 61 on the top of the rod, is to limit the movement of the sound box 43 in both directions, the only movement which is permitted being the play between the arms 59 20 and the rod 60, which is very small. The upper or inner portion of arm 42 is cut away centrally, as at 42^a, to accommodate the releasable drive connection between the carriage and shaft Z. Communicating with 25 this cut away portion, is a vertical slot 62, in which is slidably mounted a pin 63, the upper portion of which is forked and formed as a threaded nut 64, and is normally pressed upwardly by the spring 65 30 in the lower end of slot 62, into contact with a thread 66 on the shaft Z (see Figs. 7 and 8). The second spring 70, encircling the pin 63, also presses the latter upwardly. The carriage being free to move longitudinally 35 of the tube 39, the rotating of the shaft Z effects a movement of the carriage longitudinally from left to right, or otherwise from left to right along the record cylinder.

The cross piece 68 of the forked pin 63, 40 preferably has its top 69 shaped like an inverted V. On the lower end of the lever 48, is a V-shaped projection or cam 48^a, which cooperates with the cross piece 68. When the lever moves from the position 45 shown in Fig. 7 or Fig. 2, to that shown in Fig. 6, the projection on the lever engages the cross piece on the pin 63, and the latter is moved downward, thus moving the nut on pin 63 out of engagement with the 50 thread 66 on shaft Z, at which time the carriage can be moved longitudinally of the tube 39, in either direction. The projection 48^a is so disposed with reference to the lever 48, as to cause it to depress the 55 pin 63 when the cam 57^a on pawl 57 has raised the styli from the record cylinder.

Mounted on the top of the carriage 40, in a position adjacent the lever 48, is an upwardly projecting arm 71. This arm occupies 60 a fixed position and serves a double purpose. First, as a guide for the lever 48 in moving from the position shown in Fig. 7 to that shown in Fig. 2, or conversely; and second, when the lever 48 is moved to 65 the position shown in Fig. 6, to enable the

operator to move the carriage longitudinally of the machine, without exerting any considerable strain upon the lever 48.

Slidably mounted on opposite sides of the carriage 40 in suitable slots, are downwardly extending rods 72—73. The ends of these rods are provided with projecting pins 74, which take over a saddle spring 75, the center of which bears upon a pin 76 70 projecting rearwardly from the downwardly projecting arm 42 of the carriage 40. On the upper end of these rods are keys 77—78, marked respectively "B space" and "F space" in the drawings, meaning, back space, forward space. Pivoted to the 80 lower end of the rods 72—73 are pawls 79—80, which pawls are adapted to cooperate at their lower ends with the rack teeth 61 in the upper side of the rod 60.

It will be observed by reference to Figs. 85 4 and 5, that the points of the pawls 79 and 80 are not spaced at an equal distance from the sides of the arm 42 of the carriage the point of pawl 79 being nearest to the carriage and the point of pawl 80 farthest 90 away, while the point or nose of pawl 80 is in normal position disposed more nearly vertically of its pivot point than the point of pawl 79. By reason of this arrangement, the movement of the rod 73, acting through 95 the pawl 80, produces a quick forward movement, and the depression of the rod 72 and throw of the pawl 79, a slower backward movement. The rods 72—73 are each adapted to operatively engage a transverse bar 100 81, which coacts with a laterally projecting pin 82 rigidly connected to pins 63 and 68, the bar 81 having a detent finger 81^a, which engages the upper side of the pin 82. Thus, when either rod 72 or 73 is pushed downward, the pins 63 and 68 are also pushed downward, which releases the carriage from the driving shaft Z, and permits movement of the carriage forward and backward under the action of the pawls 79—80, depending upon which of the rods 72—73 is actuated. The engagement between the rods 72—73 and transverse bar 81 is provided by means of pins or studs 72^a—73^a, 105 which project over arms 81^b—81^c, on the 110 ends of bar 81, said studs being pivoted to the arm 42 of the carriage.

The rods 72—73 are normally pushed upward by the springs 65 and 70 acting through the pin 82, detent 81^a and transverse bar 81, the spring 75 normally exerting no upward pressure upon the rods 72—73. When the key 77 is depressed, the rod 72 is forced downward and pressure is exerted on the left hand end of the spring 75 through the pins 74, thereby rocking the spring and causing its right hand end to exert an upward pressure upon the pin 74 of the rod 73, thereby holding the rod 73 120 in an upward position and the pawl 80 out 125 130

of engagement with the teeth 61 on the rod 60; and the converse when the key 78 is depressed. By reason of this arrangement, the propelling action of the pawls 79—80 for the carriage in opposite directions, is rendered independent.

Projecting upward from the rear arm 59 of the bifurcated lower end of arm 42 of the carriage 40, is a plate 83, and located 10 between this plate and the arm 42 is the flat twisted strip V, which strip is round at its ends and is rotatably mounted in the standards L—M. The space between the plate 83 and the arm 42 is substantially the 15 same as the thickness of the strip V. Connected to the right hand end of the strip V (considering the machine as viewed in Figs. 3 and 4) is the bent arm U, before referred to, which is adapted, when the strip 20 V is rotated, to swing into and out of the slot T in the standard M. The rotation of the strip V is effected by the movement of the carriage 40, the twist in the strip being located near the left hand end thereof. It 25 will be apparent, that as the carriage moves to the left and engages the twist in the strip, the latter will be caused to rotate. When the carriage is at the right of the frame, the arm U is in the position shown in dotted 30 lines on Fig. 6. As the carriage moves from the right of the frame to the left, the arm U is moved into the position shown in full lines on Fig. 6, in which it projects across the end of the record cylinder. When 35 the arm U is in this position, the record cylinder 37 cannot be removed from the supporting spindle, as the arm U prevents the longitudinal movement to the right of the record cylinder, and hence danger of 40 injury to the styli, or by the styli to the surface of the record cylinder, through moving the record across the styli, is prevented. When the carriage is in the position at the 45 left of the machine, and with the lever 48 in the position shown in Fig. 6, the styli are in the neutral position and the arm U has moved up into the slot T. While it is preferred that the record be removed when the lever 48 is in neutral position and 50 the carriage member at the left, it is clear that the record may be removed with the styli in the recording or reproducing position, provided the carriage member is at the left. The record cylinder can now be 55 removed from the spindle without injury to the styli or record. I do not limit myself in any wise to the mechanism shown for moving the arm U. That shown is cheap in construction; but other means, controlled by the movement of the carriage or otherwise, may be used.

Mounted rigidly on the left hand side of the carriage 40, is a bracket 85 (see Figs. 3, 4 and 6,), and suitably supported in this 60 bracket are three plunger keys 86. This

bracket extends forwardly above and parallel to the plate P. The tops of these keys are provided with notation plates 87, marked respectively "Wire", "Listen", "Error", and the bottoms of the keys have 70 mounted thereon, dies bearing similar notations. The dies are provided with pointed ends bearing arrows, and the dies are arranged so that the arrow ends are congregated to a point, so that the with the carriage 75 in any position, whichever key is struck will indicate that position. Each of the keys is arranged to be normally pressed upward by means of a spring as shown at 88, Fig. 4, which encircles the stem of the key and bears 80 between a shoulder on the latter and the bottom of the socket 88 in which the key is guided. Located under the keys is an inked ribbon 89. The keys as a whole are mounted over the recessed plate P. Situated in the 85 bottom of this plate, is a strip of felt or other resilient material 90, upon which are placed the strips of paper Q, before referred to.

Mounted on the carriage 40 and projecting over the scale S, is a pointer 91, which is in alinement with the styli on the sound box. As the keys 86 are offset to the left of the styli the scale R on the correction strips is similarly offset from the scale S on the carriage 40, so as to cause the notations printed on the strips to agree with the position of the styli. While I have shown three keys, the number of keys may manifestly be increased or decreased as desired. The 90 operation of this part of the device is as follows:

The pointer 91 indicates the position of the recording stylus on the record cylinder. Assuming that the operator at this time 105 wishes to make a record upon the strip of paper Q, he strikes one of the keys, as for instance "Wire" whereupon there is printed upon the strip (as shown at the left of Fig. 3,) the word "Wire." This word is connected to a number on the scale, which indicates the position of the pointer at the time the key was depressed. In case the parts were in the position shown in the drawing, the word "Wire" would point to 28, which corresponds to the numeral over which the pointer 91 lies at the time. When the record cylinder is placed in the reproducing position, the reproducing operator has the 110 strip in front of him, and when the pointer reaches the number on the scale S, as for instance 5, the operator knows from the indication on the paper Q, that a message to be sent by telegraph is about to be repeated; or when the pointer has reached the number 7 115 on the scale S, that an error was made in the matter at 7; or when the pointer reaches 11, that the operator must listen for a message of some sort, concerning the matter to be reproduced. Manifestly the keys 86 can be 120 125 130

arranged to give any suitable indication. It will be understood that when the record cylinder is removed from the machine, a strip Q corresponding to such record is simultaneously removed and placed within the cylinder.

I do not limit myself to the use of keys for making notations on the strip Q. It would be possible to substitute for keys, various contrivances, such for instance as a wheel or a series of wheels as used in dating stamps and similar apparatus, such wheels adapted to rotate to bring different notations into position and to print the notations. I have not illustrated any such construction in the drawings, as such devices are old and are well known in the art of notation, dating and time stamps. Any suitable means may be employed for insuring the proper relative positioning of the scales R and S. In the present instance the scale R has a certain fixed position on the strip Q, and the latter is of a length to just fit in the recess in the plate P. A thumb notch p may be cut in the wall of the recess in the plate P, for the removal of the correction slips therefrom, and I prefer to locate such thumb notch in position to be covered by the carriage when at the right hand end of its travel.

Referring now to Figs. 9, 10 and 11, there is illustrated a resistance plug 92. This plug, in its construction presents no point of novelty. The plug is arranged to be used with direct or alternating current. In Fig. 11 the voltage of the current is indicated as 110, 210, 220. The indications D. A. stand for "direct current" and "alternating current" respectively. Assuming that the machine is to be used with a definite voltage, the resistance plug is adjusted by means of the screw 93 which interposes the required resistance between the source of current and the machine, and is then locked at this point. 94 represents a threaded plug, by means of which the device is fastened to the source of current, as for instance a lighting fixture, and 95 the wires leading to the motor in the machine (see Fig. 2). I prefer to use such a resistance plug, interposed between the machine and the source of current, and located externally of the machine, and for the reason that the interposition of resistance in a circuit is apt to create heat, which heat acts detrimentally on the motor mechanism of the machine, where the resistance is introduced into the box containing the motor.

The operation of my improved device is as follows: The carriage 40 is carried to the extreme left of the machine, and through the lever 48 the styli are brought into a neutral position. The record cylinder is then placed on the mandrel carried by the spindle Y, after which the lever is moved to bring the recording stylus into position over

the cylinder. The motor is now started by pushing the button marked "On" of the switch F. The motor then communicates motion to the spindle Y, and through the interposed gears to shaft Z. Rotation of the shaft Z produces a longitudinal movement of the carriage 40 along the shaft, whereby the recording stylus makes a spiral groove upon the surface of the record cylinder. When the record cylinder is full, the operator moves the lever 48 into the position shown in Fig. 6, and moves the carriage to the left hand end of the machine. When the carriage is at this point, the arm U is in the position shown in dotted lines in Fig. 6, and the record cylinder can then be removed; or if it is desired to reproduce the record on the cylinder, the lever 48 is shifted to bring the reproducing stylus into operation, whereupon the sounds previously recorded upon the record will be reproduced. In case, during the operation of recording, it is desired to move the carriage to the left or to the right, the keys 77 or 78 (as the case may be) are depressed, until the degree of movement in either direction required, has been obtained. In case it is desired to make a notation for the operator who will reproduce, one or more of the keys 86 are depressed. The sounds in recording and reproducing, are conveyed through the mouth piece 53 to or from the diaphragm 50.

In the foregoing description, I have not given any details of the operation of the sound recording and reproducing mechanism. I would point out, however, that the part called the sound box 43 has no function in recording or reproducing sound, but acts merely as a support for the tube 52, its mouth piece 53 and the diaphragm 50; that such so-called sound box has no gravitational action towards the record cylinder, its action being limited to a sliding movement at an inclined angle to and from the supporting frame; that the recording and reproducing of sounds are effected through the diaphragm and the styli, depending upon which stylus is in relation at the time with the record cylinder; that the diaphragm is moved by gravity towards the record cylinder and by its weight presses one or the other stylus into contact with the record cylinder, depending upon the position of the diaphragm at the time it is influenced by the action of the lever 48, and further, that the weight of the diaphragm and the pressure exerted upon the stylus, is the same whether the recording or the reproducing stylus is in contact with the record.

Having thus described my invention, I claim.

1. In a machine of the class described, a record cylinder, means for supporting and rotating said cylinder, a movable carriage by which said cylinder is moved to any de-

sired position; a sound reproducing stylus, a back-spacer in conjunction with said carriage, whereby said carriage may be moved backward and any desired part of the record 5 repeated, and a forward spacer in conjunction with said carriage whereby said carriage may be moved forward and any desired part of the record omitted.

2. In a machine for reproducing sound, a 10 record cylinder, means for supporting and rotating said cylinder, a movable carriage by which said cylinder is moved to any desired position, a sound reproducing stylus, a back-spacer in conjunction with said carriage, whereby said carriage may be moved backward and any desired part of the record 15 repeated, a forward spacer in conjunction with said carriage whereby said carriage may be moved forward and any desired part 20 of the record omitted, and means for moving said stylus out of contact with said record when either the back-spacer or the forward spacer are used.

3. In a machine of the class described, a 25 back-spacer, a pawl pivoted to the lower end of said back spacer, a forward spacer, and a pawl pivoted to the lower end of said forward spacer, the point of the pawl on said forward spacer being farther away 30 from the carriage than the point of the pawl of said back-spacer, whereby when the forward spacer key is pressed the carriage is given a quicker forward movement than the backward movement given by pressing the 35 back spacer key.

4. In a sound recording and reproducing machine, the combination with a sound record cylinder, of a device for supporting and rotating said record cylinder, and means 40 whereby both the record cylinder and its supporting and rotating device may be given longitudinal movement with respect to one another to free the cylinder from the supporting and rotating device.

5. In a sound recording and reproducing machine, the combination with a sound record cylinder, of a tapered mandrel adapted to support and rotate said record cylinder, and means whereby said mandrel may be 50 longitudinally moved toward its large end and the record cylinder moved longitudinally toward the small end of the mandrel to free the record cylinder from the mandrel.

6. In a sound recording and reproducing machine, the combination with a sound record cylinder, of a mandrel for supporting and rotating said record cylinder, said mandrel comprising a plurality of spaced rods, 60 a disc against which one end of the record cylinder abuts, and means acting through said rods adapted to cause the disc to move the record cylinder longitudinally to free it from the mandrel.

7. In a sound recording and reproducing

machine, the combination with a sound record cylinder, of a mandrel for supporting and rotating said record cylinder, said mandrel comprising a plurality of spaced rods inclined to the axis of the mandrel, a disc 70 against which one end of the record cylinder abuts, and means acting through said rods adapted to cause the disc to move the record cylinder longitudinally to free it from the rods. 75

8. In a sound recording and reproducing machine, the combination with a sound record cylinder, of a mandrel for supporting and rotating said record cylinder, said mandrel comprising a plurality of spaced rods 80 inclined to the axis of the mandrel, a disc against which one end of the record cylinder abuts, and means acting through said rods adapted to cause the disc to move the record cylinder longitudinally to free it from the rods, said means including a series of bell-crank 85 cranks engaged at one end by the rods and engaging the said discs at their opposite ends.

9. In a sound recording and reproducing machine, the combination with a sound record cylinder, of a tapered mandrel adapted to support and rotate said record cylinder, and pivoted members whereby said record cylinder may be moved longitudinally toward the small end of said mandrel, and means disposed coaxially of the mandrel for effecting the operation of the pivoted members. 90

10. In a sound recording and reproducing machine, the combination with a sound record cylinder, of a mandrel for supporting and rotating said record cylinder, said mandrel comprising a series of rods inclined to the axis of the cylinder, a member engaging 100 the rods adjacent the ends thereof which approach the axis of the mandrel, such member being adapted to impart longitudinal movement to said rods, bell-cranks pivoted adjacent the opposite ends of the 105 rods, a slidably mounted disc against which one end of the record cylinder abuts, one end of said bell-cranks engaging the said disc and the opposite end engaging said rods whereby movement is imparted to the 110 disc in an opposite direction to the direction of movement of the rods. 115

11. In a sound recording and reproducing machine, the combination with a sound record cylinder, of a mandrel for supporting and rotating said record cylinder, said mandrel including a spindle, a plate fixed thereon at one end of the mandrel, a disc slidably 120 on the spindle, a spring normally pressing said disc against the plate, a series of bell-cranks pivoted to said plate and adapted to bear at one end against said disc, a series of inclined rods adapted to be engaged at one end by the other ends of said bell-cranks, 125 and a manually operable member slidably 130

on the spindle and adapted to engage the opposite ends of said rods.

12. In a sound recording and reproducing machine, the combination of a sound record cylinder, a mandrel on which said record cylinder is supported, a spindle on which said mandrel is mounted, means for rotating said spindle, a bearing for one end of said spindle, the opposite end thereof being unsupported, and a resilient device operat-

ing in conjunction with said bearing and spindle to prevent longitudinal vibration of the spindle.

In testimony whereof I affix my signature, in the presence of two witnesses.
